HANS GEORG ULRIK, OF BUSTENARI, RUMANIA

METHOD OF AND EXPLOSIVE MEMBER FOR THE BLASTING OF BLAST-HOLES

Application filed August 15, 1929. Serial No. 386,069.

Heretofore for torpedoing blast-holes, thus for blasting open hollow spaces, in rocky ground as well as also in soft ground very strong explosive charges were used which 5 were enclosed in a thin-walled casing of sheet metal or even of cardboard only. The wall of the explosive casing has been very thin and proportioned in view of protecting the charge against moisture only. The explosive 10 members fitted with time fuses, electric fuses or percussion fuses were placed into the blast-holes of a diameter adapted to the diameter of the explosive members in such a manner, that the explosive member contacted as much 15 as possible with the surrounding wall of the blast-hole.

However when working in hard rocks, the explosion of the explosive members constructed in this way resulted in quite other 20 effects than in sand or other soft ground. In the first event clefts were formed in the rock owing to the sudden shocks, so that channels for the passage of the oil to the blast-hole were formed. Therefore explosions in 25 rocky ground yielded a favourable result if thin-walled explosive members are used. However in soft ground, for instance sand, explosions carried out with explosive members, provided with thin-walled casings 30 containing the charge, have the result that the said is subjected to a considerable outwardly directed pressure which radiates from the centre of explosion. Thereby the sand or the soft ground is compressed and 35 thus is rendered more impenetrable for the outflow of the oil.

This invention relates to an improved method of and explosive members for the blasting of blast-holes in hard, soft, sandy 40 or moist rocks or ground with the same favourable result. According to the present invention, thick-walled explosive members are used, which in view of the mechanical force of their splinters break up the rock and 45 in soft ground form channels. These explosive members are units of cylindric shape and of standard size. The charge can be determined and a projectile of any desired length can be produced by suitably combining a 50 number of units on the place of working.

The initial ignition is carried out by a percussion or time fuse of known construction, which is fitted to the projectile at the place of working.

Explosive members, provided with percus- 55 sion fuses, are dropped from outside into the blast-hole, which previously has been filled with water, and explode when striking the floor. In the case of explosive members let down by a rope, the fuse can be timed or 60 set before the insertion in the blast-hole or it can be automatically disengaged when pulling up the rope.

A suitable division of the projectile-casing by notches or by the insertion of rings, intermediate layers, washers and the like causes 65 the falling to pieces into a large number of small splinters which can be readily destroyed by drilling after the explosion. The effect of explosion is carried out preferably 70 in a horizontal direction and the danger of damaging the pipes is reduced, because the walls of the explosive member have taken up the greatest part of the explosive action, thus according to the construction more than the 75 ends of the projectile. All parts of the explosive member consists of brittle but not too hard materials.

Two modes of carrying out the present in- 80 vention are illustrated by way of example on the accompanying sheet of drawings in which—

Figs. 1 and 2 show two constructions of the explosive member in longitudinal section.

Fig. 3 is a cross-sectional view of the mem- 85 ber, the section being taken on line A—A of Fig. 2.

In the construction shown in Fig. 1, the thick-walled casing 1 of the explosive mem- 90 ber consists of a brittle material and is pro- vided at both ends with an external screw- thread 2 and with an internal screw-thread 3. The inner wall of the casing is provided with circular grooves or notches 4. Screw thread- ed caps 5, provided with holes 6 for the inser- 95 tion of a spanner, may be screwed into the internal screw-threads 3 of the casing 1.

The hollow compartment 7, remaining be- 100 tween the casing 1 and the caps 5, serves for the reception of the explosive charge, insu-

lating discs 10 being provided to protect the charge against moisture.

Screw-threaded sleeves 11, cooperating with the external screw-threads 2 of the casings 1, can be used for connecting a number of such explosive members of standard size, in order to form a unit of explosive members. In this case the screw caps 5 may be dispensed with. The individual explosive members 10 may be connected to form a unit also by means of a bayonet joint. In place of a screw cap 5, a fuse 15 is screwed into one end of the projectile consisting of a number of explosive members, while the other end thereof is shut 15 by a screw cap 5. The external screw-thread 2 at this end of the casing may be utilized for the attachment of a bracket, eye or the like through which a rope is passed in order to let down the projectile into the blast-hole.

20 In the construction shown in Figs. 2 and 3, a large number of metal rings 17, provided with notches or grooves 18 at the inner wall, are arranged within the casing 1, furnished with longitudinally extending grooves 16, in 25 order to increase the number of splinters as well as the resistance of the casing.

30 The explosion with torpedos according to the present invention is also particularly effective in very soft sandy grounds and in connection with blast-holes which for instance in view of repeated unsuccessful explosions are considerably larger than corresponds to the diameter of the explosive member. The splinters produce a large number of long 35 channels through which the oil passes from a large number of strata into the blast-hole.

I claim—

40 1. Explosive member for blasting blast-holes in soft, oil-bearing rocks, sand and the like, comprising a thick-walled casing for the explosive charge, and grooves in the casing sub-dividing the same into sections, where by the explosion the casing is torn into individual pieces according to the grooves to 45 form channels in the soft ground through which oil flows into the blast-hole.

50 2. Explosive member for blasting blast-holes in soft, oil-bearing rocks, sand and the like, comprising a thick-walled casing for the explosive charge, grooves in the casing, and rings arranged between the explosive charge and the casing which increase the resistance of the casing and the number of splinters.

55 In testimony whereof I affix my signature.
HANS GEORG ULRIK.
